UNITED STATES PATENT OFFICE

132,875

DESIGN FOR A TABLE

Joseph Cooper, New York, N. Y.

Application March 18, 1941, Serial No. 99,673

Term of patent 3½ years

To all whom it may concern:

Be it known that I, Joseph Cooper, a citizen of the United States, residing in New York, county and State of New York, have invented a new, original, and ornamental Design for a Table, of which the following is a specification, reference being had to the accompanying drawing, forming part thereof:

Figure 1 is a perspective view of the table, in closed position, showing my new design; and Figure 2 is a perspective view in partly open or leaf-extended position thereof.

I claim:

The ornamental design for a table, as shown.

JOSEPH COOPER.
